UNITED STATES PATENT OFFICE.

JOHN R. CARTER, OF CINCINNATI, OHIO, ASSIGNOR TO ERNST H. HUENEFELD, OF SAME PLACE.

STOVE.

SPECIFICATION forming part of Letters Patent No. 633,715, dated September 26, 1899.

Application filed December 28, 1897. Serial No. 663,975. (No model.)

To all whom it may concern:

Be it known that I, JOHN R. CARTER, of Cincinnati, in the county of Hamilton and State of Ohio, have invented certain new and useful Improvements in Stoves; and I do hereby declare the following to be a full, clear, and exact description of the invention, such as will enable others skilled in the art to which it appertains to make and use the same.

10 My invention relates to an improvement in stoves, and more particularly to wood-burning heating-stoves.

In the wood-burning heating-stoves now in ordinary use a fire-pot is carried within a 15 drum or jacket, and the only access to the stove is through a fuel-opening in the top of the drum or jacket and the top of the fire-pot. With such construction it is inconvenient to start a fire, as the match or torch must be 20 applied through the fuel-opening in the top, and after the fire has been started it is difficult to get at the burning logs for the purpose of rearranging them, and it is also difficult and inconvenient to remove the ashes 25 from the stove. Stoves, however, of this character possess advantages over the ordinary stoves in which the fire-pot is open at the bottom, in that they are practically airtight, the only air admitted to the fire-pot 30 entering through the draft-register, which can be adjusted to a nicety, thus permitting a slow-burning fire to be kept up without attention whatsoever for more than twenty-four hours.

35 The object of my invention is to provide a stove embodying the principal features of advantage of the wood-burning stove above described and such as is disclosed in Patent No. 601,566, granted to E. H. Huenefeld March 40 29, 1898, with a practically air-tight door carrying the draft flue or box, so that by opening the door the fire can be started, fed, and ashes removed.

45 With these ends in view my invention consists in the parts and combinations of parts, as will be more fully described, and pointed out in the claim.

50 In the accompanying drawings, Figure 1 is a view in elevation of a stove embodying my invention, the door being closed. Fig. 2 is similar view with the door open. Fig. 3 is a

view in vertical longitudinal section, and Fig. 4 is a view in transverse section of same.

A represents a stove comprising an outer jacket A', mounted on legs B and carrying 55 the inner cylindrical fire-pot C. This fire-pot is closed at its bottom and is provided at its top or side near its top with a smoke-flue D.

In the patent above referred to the only ingress-openings to this fire-pot is a fuel-opening at the top of the stove, covered by a hood, and a fixed draft-box near the bottom, and while I prefer to employ in this stove the fuel-opening at the top I provide the stove with a door E near the base of the fire-pot and attach the draft-box directly to the door, so that when the door is closed the draft for sustaining combustion is carried in through the draft flue or box in the door, and by opening the door the fire can be started, logs rearranged when necessary, and ashes removed.

An opening of the proper size is formed in the outer jacket A', and an opening a somewhat smaller, but corresponding in position to the opening in the jacket, is formed in the 75 fire-pot C, and I prefer to connect the jacket and fire-pot by a flanged collar F, completely surrounding these two openings. This collar prevents any leakage of air into the fire-pot from the hot-air space surrounding the 80 fire-pot and also prevents cinders or ashes from falling onto the floor between the fire-pot and jacket.

The fire-pot and jacket are ordinarily made of sheet-iron, and when constructed of this 85 metal I prefer to reinforce them around the door-openings by the collars or rings b b', secured thereto by the rivets or screws which secure the collar F in place.

The door E is hinged at c to the jacket or 90 to the flue-box and carries on its rear face the draft flue or box G, the door forming the front face of the flue or box. The door is provided near its upper edge with openings e, covered by a sliding damper-plate e', and the 95 rear side of the flue or box is provided near its lower end with an opening f for the escape of the air into the fire-pot. With this construction it will be seen that the air enters from above and passing downwardly through 100 the box enters the fire-pot near the base thereof.

The edges of the inner face of the box G may rest in contact with the flange g of the collar F, or, if the collar F be dispensed with, may rest in contact with the outer face of the 5 fire-pot, and with such construction the rear side of the draft flue or box G would be shaped to conform to the convex face of the fire-pot.

If desired, I can pack the contacting edges of the door and flange g or fire-pot C with asbestos, and thus provide air-tight joints. I prefer also to provide the lower portion of the door E with a mica front, so that the fire will be visible from the outside of the stove. With this construction the major portion of 15 the draft flue or box is located within the space between the jacket and fire-pot or within the space inclosed by the collar F. Hence the outer face of the door projects but slightly beyond the outer surface of the jacket and 20 resembles the ordinary draft-flue plate used on the stoves shown in application above referred to.

It is evident that many slight changes might be resorted to without departing from the 25 relative arrangement of parts herein shown and described without departing from the spirit and scope of my invention. Hence I would have it understood that I do not wish

to restrict myself to the exact construction of parts herein shown and described; but, 30

Having fully described my invention, what I claim as new, and desire to secure by Letters Patent, is—

The combination with an outer vertical jacket open at its bottom and vertical fire-pot 35 of less diameter than the jacket located within the jacket and having a closed bottom, the said jacket and fire-pot having a fuel-opening in the top, and a cover for said opening, and each also having an opening in its front 40 face, of a single hollow door or closure hinged to the jacket and bridging the space between the jacket and fire-pot, and having an air-ingress opening in its front face near its top and an egress-opening in its inner face near its 45 bottom, and a damper carried by said door or closure for closing said ingress-opening, substantially as described.

In testimony whereof I have signed this specification in the presence of two subscribing witnesses.

JOHN R. CARTER.
